UNITED STATES PATENT OFFICE

2,006,467

LIQUID DISPENSER

Frederick Lobl, Middleboro, Mass.

Substitute for application Serial No. 488,384, October 13, 1930. This application March 23, 1934, Serial No. 716,959

3 Claims. (Cl. 128—233)

This application is a substitute for an allowed forfeited application, Ser. No. 488,384, filed Oct. 13, 1930.

The present invention relates to medicine dispensing utensils commonly called medicine droppers. The ejection of exactly a single drop with the known medicine droppers was altogether dependent upon the skill of the person using the dropper. This was due to the fact that there was a common air chamber serving for both intake of medicine and ejection thereof. This chamber forms usually the interior of a bulb which when compressed effects the ejection of one or more drops of medicine. The size of drop varies with the specific gravity and the viscosity of the liquid and to some extent the drop varies also in size with the conditions under which it is formed. A drop is usually considered equal to a minim but varies considerably from this value.

It is an object of the invention to provide an improved medicine dispenser by means of which very small quantities of liquid are ejected in predetermined volume. This object is achieved by providing the bulb of the medicine dispenser with two chambers communicating with each other, but both chambers being closed to the outer air when the implement is in use. One of these chambers is of such size that compression of that portion of the bulb which may be termed the ejecting portion thereof, will cause the ejection of exactly the intended predetermined quantity of liquid. Particularly when toxic substances are applied it is of greatest importance to observe strictly the prescribed dose.

The drawing illustrates two different forms of construction of the subject-matter of the invention.

In the upper figure of the drawing one form of construction of the improved medicine dispenser is shown. It comprises a tube or stem 4 having at its reduced terminal portion 2 an orifice which serves to admit entrance or ejection of liquid when the bulb 6 is on the one hand first compressed and then released and on the other hand only compressed. The bulb 6 consists of rubber or other suitable flexible material and has a flange 8 which creates an airtight union of the bulb with the tube 4 which usually consists of glass. If desired, however, the bulb and tube may be made integral as in an ear, eye, or ulcer syringe.

In accordance with the invention the rubber

bulb has, besides the usual chamber 12 which forms the hollow interior of the portion 6 of the bulb, an additional chamber 14 which is the interior of the portion 10 of the bulb. Both chambers are in direct communication with each other but they are closed to the outer air. The size of the chamber 14 of the portion 10 is so selected that a predetermined volume of liquid will be ejected when the portion 10 of the bulb is fully compressed. It is, of course, understood that the construction is such that by compressing the portion 10 either a single drop or a predetermined number of drops will be ejected. It is also obvious that my invention may be employed for dispensing measured drinks, such as fingers of whiskey, etc.

In the modification shown in the lower figure of the drawing the shape of the bulb 6, 10 differs from the one shown in the upper figure. However, the function of the modification is the same as described in connection with the upper figure.

Having thus described my invention what I claim as new and desire to secure as Letters Patent of the United States is:

1. A liquid dispenser having in combination a delivery tube and an elastic compressible bulb communicating with said tube, said bulb having a main chamber and an auxiliary chamber of predetermined volume solely in communication with said main chamber, whereby complete compression of said auxiliary chamber wall causes a predetermined volume of liquid to be delivered from said tube.

2. A bulb of elastic compressible material for a medicine dropper having a main chamber with a delivery opening and an auxiliary chamber of predetermined volume solely in communication with said main chamber, whereby complete compression of said auxiliary chamber wall causes a definite volume of liquid to be delivered from the dropper.

3. A liquid dispenser having in combination a delivery tube and an elastic compressible bulb in communication with said tube, said bulb having a main chamber and an auxiliary chamber of a volume of one-half to two minims solely in communication with said main chamber, whereby complete compression of said auxiliary chamber wall causes a single drop of liquid to be delivered from said tube.

FREDERICK LOBL.
